BRASSIÈRE

Henry Rasch, Hohokus, N. J., assignor to Chain-craft, Inc., Haverstraw, N. Y., a corporation of New York

Application March 20, 1935, Serial No. 11,904

6 Claims. (Cl. 2—42)

This invention relates to brassières which may be employed independently or in combination with women's undergarments and garments.

The general object of the invention is to provide a snug-fitting yet comfortable breast support which is self adjustable and readily adapted to conform to different requirements of wearers whose breast and waist sizes and breast positions are different.

10 A feature of the invention resides in the provision of a brassière having a plurality of overlapping breast supporting elements, no one of which is alone sufficient adequately to provide proper support.

15 Another feature of the invention resides in the provision of a plurality of elements, slidably arranged in overlapping position, whereby two elements cooperate to support each breast, but all elements adjust themselves with respect to each other to compensate for variation in size of individual breasts, and to allow for growth or diminution of individual breasts and waist lines.

20 A further feature covers the use of an elastic insert or the like for joining the extremities of two breast supporting elements, whose opposite extremities are attached to non-elastic end pieces, in combination with a superposed element whose extremities are attached to elastic inserts connecting to said end pieces.

25 Another feature provides for an inner supporting portion and an outer supporting portion, one of said portions having an extensible element integral therewith and connecting two parts thereof, the other portion having extensible elements attached to the ends thereof, the length of each portion thereby being adjustable individually and with respect to the other portion.

30 A further feature provides for two overlapping portions cooperating with each other to provide two supporting pockets, one of the portions fitting within a loop on the other portion and being adapted to be adjustably positioned with respect to the other portion.

35 Further features, including modifications and alternative arrangements, capable of providing highly novel and useful features of breast support in a brassière of superior construction and arrangement of elements will be more apparent from the following description of two typical forms of the invention to be read in connection with the accompanying drawing, in which:

40 Fig. 1 is a fragmentary perspective view, partly broken away, of one form of the invention;

Fig. 2 is a perspective of the full construction of the brassière shown in Fig. 1; and

Fig. 3 is a perspective of a modified form of the invention.

Considering the drawing, similar designations referring to similar parts, numeral 4 designates a cover piece, one for each breast, and 5 is a shoulder strap, attached to and connecting each cover piece with end pieces 6, of Fig. 2, and elastic encircling bands 7 of Fig. 3.

10 In the arrangement of Figs. 1 and 2, an inner supporting portion 8 is stitched or otherwise suitably fastened to the cover pieces along the seams 9, 9. These seams, as shown, extend about half the length of each cover piece. In practice, the portion 8 may consist of two pieces fastened by a centre seam 10 which continues to connect together the cover pieces. From the seams 9, the portion 8 is cut out, as shown, by lines 11, diminishing in size to a narrow width 15 which is attached at each end to an elastic or extensible insert 12 which connects in turn to end pieces 6.

20 An outer supporting portion 13 is stitched or otherwise suitably connected to the cover pieces 25 along the seams 14, 14, these seams 14 extending about half the length of each cover piece starting from end pieces 6. Portion 13 is also attached to the end pieces along seams 15, 15, which also connect the cover pieces 4 to the end 30 pieces 6. In practice, the portion 13 consists of two pieces, each cut out, as shown by lines 16, 16, diminishing to form two narrow widths which are connected together by an elastic insert 17, of similar width. Insert 17 is positioned within loop 35 18, superposed on centre seam 10. The lower edge 19 of portion 13 may be above the lower edge 20 of portion 8, to provide greater cooperative support between the two portions.

25 The fastening piece 21, preferably of elastic material, having eyes for connecting with hooks at the opposite end of the brassière, completes the construction of Figs. 1 and 2.

30 As a result, we have two portions, each unattached at the bottom, each attached to part of 45 the cover pieces, each extensible, and each independently extensible and adjustable with respect to the other.

35 In Fig. 3, the same general features are employed except that the inner portion 8 does not 50 have its ends fastened to elastic inserts 12, but instead has each end connect, by a button 21a, or otherwise, to one end of an elastic band 7, whose other end connects with the opposite end piece 6. The bands 7 encircle the body and pro- 55

vide an extensible and movable characteristic to portion 7, which thereby may be adjusted in position upward or downward and sidewise along the body. The outer portion 13 is constructed 5 as in Figs. 1 and 2 with the elastic insert 17 between the two component breast supporting pieces. The straps 5 may have their unattached ends slidably positioned on bands 7, as shown.

Thus, each breast will be supported by two cut 10 out overlapping elements, movable with respect to each other, depending upon the size and natural form of the breast. A snug and comfortable fit, as well as proper support will thereby be imparted regardless of variations in size of individual breasts of the wearer and of waist lines, and this construction enables different persons 15 with different requirements to be accommodated with brassières having the same size elements.

The construction may be varied by combining 20 parts, by reversing the inner and outer portions, and otherwise by resorting to differences in cut of elements, assembly of parts and variations in manner of imparting elastic characteristic to the overlapping pieces.

25 I claim:

1. A brassière comprising a plurality of breast supporting elements, end pieces, a first of the elements being fastened to said end pieces by resilient ties, and other of the elements being fixedly attached to the end pieces and secured to each other by resilient means, the first element being slidable with respect to the other elements. 30

2. A brassière comprising a rear portion, a plurality of breast supporting elements, a first of the elements being fastened to said rear portion by resilient ties, and other of the elements being fixedly attached to said rear portion, and secured to 35

each other by resilient means, the first element being slidable with respect to the other elements.

3. A brassière comprising a pair of breast supporting pockets, each pocket including a cover piece and a pair of contiguous overlapping elements, said elements when in breast-supporting position being in contact with each other proximate the center of each pocket, said elements being adjustable with respect to each other, and elastic bonding means in combination with said 10 elements to permit lateral expansion of the brassière.

4. A brassière comprising a first element for supporting both breasts, a loop on said element, a second element for supporting one of the breasts, 15 a third element for supporting the other of the breasts, said second element and said third element being joined to each other through said loop.

5. A brassière comprising a pair of breast supporting pockets, each pocket comprising an upper portion and a lower portion, the lower portion of each pocket comprising a pair of contiguous overlapping elements, the different overlapping elements of a pocket supporting different portions 25 of the lower part of the breast supported by said pocket.

6. A brassière comprising a pair of breast supporting pockets, each pocket for each breast including a cover piece and a pair of contiguous 30 overlapping elements for supporting the underside of the breast, the two overlapping elements of each pocket being adjustable with respect to each other, the two overlapping elements of each pocket supporting different portions of each of the 35 breasts.

HENRY RASCH.
